Patented May 26, 1903.

UNITED STATES PATENT OFFICE.

ANDREW FYRBERG, OF WORCESTER, MASSACHUSETTS.

REVOLVER.

SPECIFICATION forming part of Letters Patent No. 728,896, dated May 26, 1903.

Application filed October 28, 1901. Serial No. 30,186. (No model.)

To all whom it may concern:

Be it known that I, ANDREW FYRBERG, of the city and county of Worcester and State of Massachusetts, have invented certain new and useful Improvements in Revolvers; and I do hereby declare that the following is a full, clear, and exact description thereof, reference being had to the accompanying drawings, forming a part of this specification, and in which—

Figure 1 represents a top or plan view of so much of a revolver as is necessary to illustrate my improvements thereon. Fig. 2 is a side view thereof with the barrel and cylinder locked in position for firing. Fig. 3 is a similar side view of the parts shown in Fig. 1 with the barrel unlocked and swung down with the cylinder in position to extract the cartridges preparatory to reloading said cylinder. Fig. 4 is a vertical longitudinal section taken on line *a*, Fig. 1, looking in the direction of arrow *a'*, showing a side view of my improved barrel and cylinder locking mechanism hereinafter described. Fig. 5 is an enlarged transverse section, shown partly in side view, through part of said barrel and cylinder locking mechanism, taken on line *e*, Fig. 2, looking in the direction of the arrow. Fig. 6 is a bottom view of the parts shown in Fig. 4 looking in the direction of arrow *b*, and Fig. 7 is a similar view to Fig. 6 with the flat spring for holding the thumb-latch of the barrel-locking-device left off to more clearly illustrate the parts coming under the same.

My invention consists of certain improvements in the construction of the mechanism for locking the barrel to the frame and for holding the cylinder in position longitudinally, as will be hereinafter more fully set forth.

In order that others may better understand the nature and purpose of my said invention, I will now proceed to describe it more in detail.

Referring to the drawings, *A* represents the frame; *B*, the barrel, pivoted at *C* thereto. *D* is the backward-extending top frame of the barrel, adapted to be attached and detached to and from said frame *A*, and *E* is the cylinder of the revolver, provided with the usual spring extractor-spindle *F* and head

F', the inner end of which extractor-spindle engages with the finger *G'* of the extractor-disk *G* when the barrel is swung down, as is shown in Fig. 3.

The hammer and trigger mechanism constitutes no part of my improvements, and it is therefore deemed unnecessary to illustrate or describe the same.

My improvement comprises in combination the thumb-latch *d*, pivoted at its inner end to the transverse pin *e*, and whose outer end is adapted to hook over the vertical projections *f* on the frame *A*. Said thumb-latch *d* is provided with the usual laterally-projecting hubs *d' d'*, having milled ends to facilitate holding the same between the thumb and forefinger in operating the latch and are adapted to fit against the outer ends *g g* of top frame *D*. The latch is held with a yielding pressure in said position, which is its normal position, by means of a flat spring *h*, fastened at its forward end by a screw *h'* to the top frame *D*, and whose free end bears upward against the under side of the forward 70 or inner end *i* of said latch.

Under the pivot *e* of latch *d* is arranged a pawl *j*, pivoted at its forward end to a transverse pin *k* and provided at its opposite or rear end with a hook *j'*, adapted to hook over the edge of the outer end of the cylinder *E* to hold it from slipping out of position longitudinally. Said hooked end *j'* lies in a central vertical slot formed in the under side of the latch *d*, (see Figs. 6 and 7,) thereby insuring 85 said pawl from tipping laterally. The forward or inner end of said pawl *j* is provided with a longitudinal stud *l*, projecting forward into a spiral-shaped longitudinal groove *m'*, formed in a transverse spindle *m*. Said spindle *m* is fitted to slide longitudinally in its bearing. A constant yielding pressure is imparted thereto to push it outward by means of a spiral spring *n*, arranged in an opening between the inner end of said spindle *m* and the wall of top frame *D*, as is shown in Fig. 5. The outward movements of the spindle are controlled by means of a set-screw *o*, whose inner end fits in a slot formed in the spindle, as is also shown in Fig. 5. Said 100 spindle may, therefore, as will be seen, be pushed inward longitudinally a short dis-

2
tance, and when said pressure is released the spring n forces it out again to its normal position, as is shown in the drawings. The purpose of said spirally-grooved spring-spindle m is to operate the hooked end j' of pawl j in and out. This is done by the longitudinal operation of the spindle, as aforesaid, through the connection previously described—viz., of the stud l engaging with the spiral groove m' .
 10 The spindle is held from turning, as well as from moving, beyond its proper longitudinal limits by the set-screw o . Therefore it is obvious that since the pawl is attached to a fixed pivot k when the spindle is moved in or out longitudinally the stud is forced to travel in the spiral groove, and consequently moves the hooked end j' out or in, according to which direction the spindle is moved. In practice the normal position of the pawl is
 15 as shown in Fig. 4, with the hooked end j' projecting beyond the under surface of top frame D , so as to hold the cylinder as is shown in Figs. 2 and 3, the spindle m occupying its outward position at this time, as is
 20 shown in Figs. 5, 6, and 7. Being thus made and adjusted, it will be apparent that by pushing inward on the end p of the spindle the stud will be caused to travel along the spiral groove m' , and thereby moves the
 25 hooked end j' of the pawl inward to unlock the cylinder, so that it may be removed.
 The above-described cylinder-lock device is simple in construction, positive in action, and strong and durable, as I have fully demonstrated in practice.
 30 It will of course be understood that no claim is made, broadly, to any of the features hereinbefore described and shown in the drawings, my invention being limited to sub-

stantially the construction adopted and set forth in the claims.

What I claim as new and of my invention, and desire to secure by Letters Patent, is—

1. In a revolver, the combination of top frame D the upper part of frame A , and cylinder E , with the thumb-latch d , its pivot e , spring h , fastened at one end to said top frame D , and whose free end bears against the inner end of thumb-latch d ; lever j , arranged under pivot e , and provided with the hook j' at its rear end, and also provided with the stud l at its forward end; the pivot k of said lever, transverse spindle m , provided with the spiral groove m' adapted to receive the aforesaid stud l ; spring n , for exerting a longitudinal pressure on spindle m , and means for controlling the longitudinal movements of said spindle and for keeping it from turning, substantially as and for the purposes set forth.

2. In a revolver, the combination of top frame D and cylinder E , with transverse spindle m , fitted to slide longitudinally in said top frame, and provided with a spiral groove m' , spring n for exerting a longitudinal pressure against said spindle, means for controlling the longitudinal movements of the spindle and for preventing it from turning; lever j , provided with a stud l at its forward end adapted to engage with the spiral groove m' , and also provided with a hook j' at its opposite end adapted to fit over the outer edge of the cylinder, and the pivot k of said lever, substantially as and for the purpose set forth.

ANDREW FYRBERG.
